Inventor:

C. Dorflinger

UNITED STATES PATENT OFFICE.

CHRISTIAN DORFLINGER, OF BROOKLYN, NEW YORK.

IMPROVEMENT IN LAMP-TOPS.

Specification forming part of Letters Patent No. **36,079**, dated August 5, 1862.

To all whom it may concern:

Be it known that I, CHRISTIAN DORFLINGER, of Brooklyn, Kings county, State of New York, have invented a new and Improved Top for Lamps Burning Kerosene, Coal, and other Fluids or Oils; and I do declare that the following is a full and exact description thereof, reference being had to the accompanying drawing, viz.:

The making of the top of the lamp-burners, where the chimneys fit on, oval instead of round, to receive the base of an oval chimney, such oval top being designed to insure that oval chimneys can only be used in their proper position—viz., so that the long axis of the oval shall run through the entire breadth of the flat wicks used in such lamps, and to com-

pel the breadth of the flame to correspond with the greatest breadth of the oval chimneys, and also that the screw, spring, or other fastening, being applied on one of the flat sides of the oval, shall hold the chimney more secure than it can be done on a round top.

What I claim as my invention, and desire to secure by patent, is—

The making of the top of lamp-burners oval instead of round, so as to receive and fit all oval-base lamp-chimneys, in the manner and for the purpose herein set forth.

New York, June 13, 1862.

C. DORFLINGER.
